COMBINED VIAL STORAGE AND DISPENSING BIN

Bernard Gavrin, 57—32 263rd St., Little Neck, N.Y.

Filed Mar. 28, 1961, Ser. No. 64,519

Term of patent 14 years

(Cl. D52—2)

FIGURE 1 is a perspective view of a combined vial storage and dispensing bin showing my new design;

The undisclosed side of the bin is substantially the same in appearance as the side shown.

I claim:

The ornamental design for a combined vial storage and dispensing bin, substantially as shown and described.
